HOUSING FOR A ROTARY MOWER

Charles Buford Coss, Neodesha, Kans., assignor to Independent Manufacturing Co., Inc., Neodesha, Kans., a corporation of Kansas

Filed July 15, 1966, Ser. No. 3,098

Term of patent 14 years

(Cl. D40—1)

Fig. 1.

Fig. 2.

Fig. 3.

Fig. 4.

FIG. 1 is a front perspective view of the housing for a rotary mower;

FIG. 2 is an elevational view of one side thereof, the opposite side being the same in appearance;

FIG. 3 is a top plan view; and

FIG. 4 is a rear elevational view of the housing for a rotary mower.

The broken lines are shown for illustrative purposes only.

I claim:

The ornamental design for a housing for a rotary mower, as shown and described.
